mesne assignments, to Underwood Elliott
Fisher Company, New York, N. Y., a corpora-
tion of Delaware

Application April 25, 1932, Serial No. 607,275

56 Claims. (Cl. 235—60)

This invention relates to combined typewriting and computing machines in which an indexing mechanism is set up by operation of the numeral-type-keys and the accompanying typewriter-carriage letter-feeding movements preparatory to running the typed amount into one or more totalizers.

This application has to do mainly with means whereby the states of a plurality of registers, in respect to adding, subtracting or non-computing, are selectively and individually determined preparatory to operation of the numeral-keys in a computing zone, and relates to my co-pending application, Serial No. 324,353, filed December 7, 1928 (now Patent No. 1,927,951, dated September 26, 1933).

Each of the several registers with which the machine may be provided has a set of reciprocating bars for rotating the dial-wheels, said bars being each provided with a row of digit-pins, the several pin-bar groups and the members thereof in their normal retracted positions being disposed in parallel and transversely aligned array across the computing mechanism which is surmounted by the typewriting machine. A row of digit-bars depressible edgewise extends across the pin-bars and over the pin-groups and has operative connections with the numeral-type-keys, so that, upon operation of any numeral-key, a corresponding digit-bar is depressed for setting corresponding digit-pins in the several sets of pin-bars.

The pin-bars are normally in retracted positions, so that a descending digit-bar passes idly between the pins. By advancing the pin-bars slightly to bring them under the key-operated digit-bars, the latter are enabled to set the pins. By the use of suitable trains extending from the pin-bars to the typewriter-carriage, this slight advance of the pin-bars is effected seriatim in denominational order, in any pin-bar group, by the letter-feeding movements of said carriage, it being understood that said movements accompany the operation of the numeral-type-keys, and that they are, in respect to the computing mechanism, denomination-determining steps.

As shown in my co-pending application, No. 472,610, filed August 2, 1930, a single or trunk set of denominational trains common to all the pin-bar groups is acted upon by the carriage, each individual train being ramified to serve all the pin-bars of corresponding denomination in the several pin-bar groups. Each group of ramifications includes couplers shiftable as a group to connect said ramifications to the pin-bars, the

couplers being normally in ineffective positions. By means of these shiftable couplers, it is determinable which group or groups of pin-bars shall be indexed during the passage of the carriage through a computing zone, and hence which register or registers shall be called into action. A coupler-shifting train extends from each coupler-group to the carriage for control by the latter as it enters and leaves a computing zone, said carriage having one or more tappets for selectively actuating the coupler-trains, and being thus enabled to determine, preparatory to the denominational pin-bar-selecting operations by said carriage upon the denominational trunk or master trains, which groups of pin-bars are to be called into action.

Following the typing of an amount in a computing zone and the concomitant setting of corresponding digit-pins in one or more pin-bar groups, the machine may be cycled to run said amount into the registers of the selected pin-bar groups. The cycling mechanism or general operator includes a reciprocating cross-bar extending transversely of and below all of the pin-bars, so that in the advance stroke of said cross-bar, the latter may engage the depressed pins and advance the bars to extents depending upon which digit-pins were depressed, it being understood that the several depressed pins form differently positioned lugs, on their respective pin-bars, and are projected into the path of said cross-bar. For rotating the register-dials, they have pinions and the pin-bars have racks, said bars being straightly elongate and extending from front to rear of the computing mechanism, the racks being at the forward ends of the pin-bars and the dial-wheel pinions overlying the racks and being normally out of mesh therefrom.

As shown in said application No. 324,353, the dial-wheels are rotatable in reverse directions, one direction being for addition, and the opposite direction being for subtraction. To accomplish opposite rotations of the dial-wheels, each pin-bar rack has always in mesh therewith an idle gear disposed behind the dial-pinion, the dial-pinions also being normally out of mesh with their respective idle gears.

At the beginning of the cycling operation and before the general-operator cross-bar starts the advance of any pin-bar, the selected register-wheels are shifted either downwardly to mesh directly with the racks for rotation in one direction, as in addition, or else they are shifted rearwardly to mesh with the idle gears for rotation in the opposite direction, as for subtraction. The

register-wheels having thus been meshed one way or the other, the pin-bars are advanced forwardly to extents corresponding to the setting of the digit-pins, plus extra carrying steps, the latter being effected when required, by carry-over mechanism fully set forth in my co-pending application, No. 601,173, filed March 25, 1932, and hereinafter generally described. By the forward advance of the pin-bars, the indexed amount is accumulated in the dial-wheels which must be unmeshed from the racks, or from the idle gears if they have been meshed with the latter, before the general operator in its return stroke picks up any pin-bar. To enable the general operator 10 to return the pin-bars, each of the latter has a lug extending into the path of the general operator cross-bar. Said lugs are so disposed that there is an idle period at the beginning of the return stroke of said cross-bar, which affords 15 time for unmeshing the dial-wheels.

For shifting the dial-wheels, each set thereof is mounted in a frame arranged and mounted for swinging said frame, and hence the dial-wheels, downwardly and upwardly, for meshing and unmeshing the dial-pinions with or from the pin-bar racks, as in addition, or for shifting said frame rearwardly and forwardly for meshing and unmeshing the dial-pinions with and from the aforesaid idle gears, as in subtraction. Each 20 shiftable dial-frame includes two side plates, each side plate having at its rear a horizontal slot slidably fitting a cross-rod of the general framework. A tie-rod at the front ends of said plates spaces the latter apart and slides in a normally 25 horizontal slot of a vibratory arm extending rearwardly from a fulcrum. Arms extending vertically from a fulcrum are also connected to the plates. It will be seen that if the horizontal arm is vibrated, the vertical arms remaining stationary, 30 the dial-wheel frame, whose rear slots embrace the aforesaid cross-rod, will swing about the latter as a fulcrum, and thereby move the dials down or up, said dials being positioned on an arbor spaced substantially forward of said cross-rod. 35 It will also be seen that if the vertical arms are vibrated, the horizontal arm remaining stationary, the frame will be shifted rearwardly or forwardly, being guided by its own horizontal slots and the slot in the stationary horizontal arm.

The present invention provides improved carriage-controlled state-determining means for each of the several registers, each state-determining means being normally held in a neutral state and being conditioned additively or subtractively concomitantly with the selection of its 40 companion register. Thus, with a series of say seven registers, it is necessary for the carriage in entering a computing zone to act upon only one state-determining means if say only one register 45 is to be called into action in said zone. As hereinbefore mentioned, a register is selected by shifting its aforesaid group of pin-bar couplers into effective position by the train extending from said coupler-group to the carriage. It will be 50 remembered that there is one such train for each register. It is contrived to have the actuation of this train cause the withdrawal of a stop to release a corresponding state-determining means, 55 to enable the latter, under a suitable influence, as, for example, a spring, to assume an additive position determined by a second stop, which may also be withdrawn by the carriage, whereupon the state-determining means, still under said influence, will assume a subtractive position. Each 60

register has its individual state-determining means including said stops.

It is also contrived that the several state-determining means may assume their selected positions as soon as the aforesaid latches are caused 5 to be withdrawn by the carriage. Heretofore, state-determining means were restored by the general-operator cross-bar and, therefore, could not assume their selected positions until said cross-bar had advanced sufficiently at the begin- 10 ning of the cycling operation.

As has been mentioned, the cross-bar does not immediately pick up any pin-bar at the beginning of its advance stroke, and, therefore, there is an idle period at the beginning of the cross- 15 bar advance stroke, which affords time for meshing the dial-wheels with their drive-racks or with their idler gears. It is desired to allot as much as possible of this idle period to the meshing operation to avoid harsh abruptness of said operation. It is obviously a disadvantage, therefore, to use part of this idle period for enabling the state-determining means to assume their selected 20 positions, it being understood that the dial-wheels may not be meshed until said positions 25 have been assumed, inasmuch as said positions determine whether the dial-pinions are to mesh with the racks or with the idler gears.

Immediate movement of the state-determining means to their selected positions as soon as the 30 carriage is tabulated to a computing zone also affords a further advantage and novel feature of the present improvements, inasmuch as there are provided means actuated by a member whose position is a positive indication of the state of 35 the state-determining means; and, by said actuated means, a positively correct and visible signal may be given to the operator as soon as the carriage enters a computing zone, so that said operator may observe what the ensuing state of 40 each register will be in a subsequent cycling operation.

A further feature of the improvement resides in the provision of means whereby the dial-wheel meshing and unmeshing operations for the several registers, even though the latter are in different states in respect to adding or subtracting, 45 are driven positively by the general operator.

Another feature of the improvements resides in the provision of manually-operable means, 50 whereby any state of a register as determined by the carriage may be altered. In other words, while preserving the feature of causing the immediate movement of the state-determining means to their selected positions as an accompaniment 55 of the selection of their corresponding registers, it is contrived by appropriate means to enable the resetting of said state-determining means of the selected registers to positions other than the positions determined by the carriage. Thus, if 60 a state-determining means is caused by the carriage to be positioned for subtraction, it may, by manual controls, be changed for addition or for neutral, or a carriage-determined addition-setting may be changed to neutral or subtraction. 65

For shifting the several registers differentially during a cycling operation, that is, some registers for addition and others for subtraction, or all registers for addition or all for subtraction, there is provided a rotary shaft, connected to the power-driven general operator, and having cams driving positively in each direction a reciprocatory member connected to a rock-shaft which extends transversely in front of all the shiftable dial-frames.

The aforesaid horizontal and vertical arms for each of said frames used to shift the latter to adding and subtracting positions are loosely mounted on said rock-shaft, which has additionally for each register a coupler slideable axially along and splined to said shaft. Sliding a coupler along said shaft in one direction preparatory to the cycling operation connects it with the corresponding vertical arms, whereupon rocking of the shaft, at the beginning of said cycling operation, will shift the corresponding dial-wheel frame rearwardly to mesh the dial-pinions with the idler gears for subtraction. If the coupler is shifted in the opposite direction, it will be connected with the corresponding horizontal arm, so that in the rocking of said shaft, the dial-wheels will be shifted downwardly to mesh with the racks for addition. Conversely, if the rock-shaft be rocked in the opposite direction, the dial-wheels will be unmeshed from the idler pinions in one case when the coupler is connected to the vertical arms, and from the racks in another case when said coupler is connected to the horizontal arm. The wheel-shifting coupler is normally in an intermediate position, in which case neither the horizontal arm nor the vertical arms are connected to the rock-shaft, and the register is then in a neutral state. This neutral state of a register may obtain during a cycling operation and during the cycling.

For shifting the rockable couplers and affording a non-rocking coupler-controller, there is provided for each coupler an auxiliary slide mounted for movement in coupler-shifting direction and having a notch articulated with a tongue of said coupler in a manner to permit rocking of the latter.

The aforesaid latches, that is, the ones that are connected to respective pin-bar couplers of the several registers and the ones that are connected to a subtraction-setting train controlled by the carriage, are in the rear of the computing mechanism. Each pair of latches, that is, a subtraction-latch and a latch connected to a pin-bar coupler, retains a straightly elongate slide extending from the rear of the machine to the front, and carrying at its front end a cam-head formed with a closed cam-groove for actuating the aforementioned non-rocking coupler-controller which has a downwardly-projecting tongue embraced by said cam-groove. Thus, when one or both latches that retain said slide are released, the latter, under the pull of a suitable spring, moves forwardly, and, by means of said cam-groove, moves the rock-shaft-coupler controller to positions corresponding with the extent of movement of said latch-retained slide.

Inasmuch as said latch-retained slide is positively keyed by means of the closed cam-groove at the end thereof to the rock-shaft-coupling controller, and as the latter, in turn, is positively keyed to the coupler, the position of said latch-retained slide is a positive index-basis of the position of the rock-shaft coupler. It is contrived, therefore, to connect to said latch-controlled slide a shiftable signal-member preferably in the form of a vertical shaft having at its lower end an arm linked to said slide and carrying at its upper end a plate inscribed with the signals "S" and "A", signifying subtraction and addition. Said shaft is mounted so that said signals may register with a sight-opening in the casing close to the sight-opening for the dials of the corresponding register. When the state-

determining means are in neutral positions, a blank portion of said plate registers with said sight-opening to signify that a neutral condition obtains in the state-determining means. There is one of such signal-devices for each register. 5

It is further contrived to extend the elongate latch-controlled slide sufficiently forward, so that it may be manually shifted back, or its forward movement manually controlled, by suitable means, preferably a bell-crank lever fulcrumed within the casing of the machine, and having an arm extending forwardly through and beyond the front of said casing to carry a key. A transverse arm of said lever may engage the front end of the latch-controlled slide, and it will be seen that by turning said lever, said latter slide may be pushed back, or its forward movement limited, said lever thus affording a manual control for determining the position of the latch-controlled slide independently of the carriage. Suitable detent-means are provided to hold said bell-crank lever at its three stations, namely, for neutral, addition and subtraction. As a further manual control of the latch-controlled slides, all the subtraction-latches for the several latch-controlled slides are operable by and connected to a common rock-shaft, operable either by a manually-controlled general-subtraction key or by a normally-latched spring-pressed lever under the control of the carriage. Thus a single tappet on the carriage suffices in any computing zone to effect subtraction in a selected register. In cases where another register is to be simultaneously selected and conditioned for addition, the release of the subtraction-latch therefor may be negated by setting the aforesaid manually-operable bell-crank key of said latter register to addition position. Similarly, if registers are selected by the carriage and conditioned for addition or subtraction, and it is desired for some reason to have them neutral, the manually-operable bell-crank keys for said other registers are set to neutral positions to prevent advance from neutral positions of their respective latch-controlled slides. 35

Toward the end of the cycling operation, a universal member extending transversely of all the latch-controlled slides is moved backwardly to restore said slides to their rearward positions, the several latches being permitted at this time to drop into latching positions and hold said slides. Said universal member is driven by the general operator, and, before the end of the cycling operation and after it has restored the latch-controlled slides, it moves forwardly again, so that said slides may be set forwardly again by their springs when the latches are released in the next computing zone. Thus each slide and its associated state-determining means may assume their selected positions as soon as the carriage enters said zone. 40 50 55 60

There is provided for each register the usual star or clearance key operable when all the wheels stand at zero and being locked when the wheels stand otherwise. Inasmuch as the dial-wheels shift during a cycling operation and the star-key-locking member shifts with said wheels, it is possible to operate said key erroneously during the cycling. The aforesaid rock-shaft-coupler-shifting controllers afford novel controlling means for the star-keys, in that each of said controllers 65 70 75 may have an abutment to lock the star-key when said slide is in adding or subtracting position, and may also have a clearance for said key when the slide is in neutral position. It is thus obvious that no star-key of a register may be operated 75

while its dial-wheels are shifted from normal position.

Other features and advantages will hereinafter appear.

5 In the accompanying drawings,

Figure 1 is a perspective view, showing the arrangement of the manually-operable subtraction-key and the means whereby it actuates the rock-shaft to which the subtraction-latches are connected.

10 Figure 2 is a side view of the combined typewriting and computing machine, many parts being omitted to show clearly the means in which the invention is embodied.

15 Figure 3 is a side view, showing a pin-bar advanced by the general operator to rotate the dial-wheels for subtraction, the state-controlling and dial-shifting means being shown in their subtracting positions. There are also shown the carriage-controlled latches resting on top of the slide which they control, ready to re-engage said slide upon the restoration of the latter by the universal-slide-restoring member.

20 Figure 4 is a perspective view, showing details of the manually-operable bell-crank or state-setter at the front of the machine, and its relation to the front of the latch-controlled slide. Details of the rock-shaft-coupling controller and its mounting are also shown.

25 Figure 5 is a perspective view of a register, showing details of the shiftable dial-wheel frame and the star-key mechanism, and details of a member whereby the register-shifting rock-shaft is splined to the shiftable coupler thereon.

30 Figure 6 is a skeleton perspective, showing the arrangement of the parts for four registers, four sets of state-determining means being shown, together with the latches therefor, and the means for controlling said latches.

35 Figure 7 is a perspective view, showing details of the means whereby the carriage releases a spring-pressed lever for rocking the subtraction-rock-shaft to effect the withdrawal of the subtraction-latches. Said Figure 7 is shown in juxtaposition to Figure 6 to illustrate the co-operation of the parts.

40 Figure 8 is a top plan view, showing details of the signal-device and the bell-crank lever or state-setter at the front of the machine.

45 Figure 9 is a partial side view, showing the operated positions of the means whereby the subtraction-latch rock-shaft is released, and also showing the operated position of the universal member that restores the latch-controlled slides, and the operating means therefor.

50 Figure 10 is a detail front view, showing how the latch-controlled slides are slidably supported at their rear portions.

55 Figure 11 is an enlarged perspective view, showing two registers, and bringing out details of the register-shifting rock-shaft and its equipment, and also showing details of the manually-operated bell-crank, the power-head for shifting the dial-wheels, and its operating cams, and the connection of said power-head to said rock-shaft.

60 Figure 12 is a view similar to Figure 3, showing how the dial-wheels are directly engaged with the racks for addition, and showing the corresponding positions of the dial-shifting means, the rock-shaft-coupling means, and the power-head that actuates said rock-shaft, the parts being shown as when the cycling operation is at the point where said dial-wheels have just become engaged with the racks.

65 Figure 13 is a perspective view, including a

portion of the dial-wheel-shifting rock-shaft and the coupling means for one of the registers, and showing particularly the coupler shifted to engage the horizontal adding arm, and the connection of said coupler to its operating controller.

70 Figure 14 is a rear elevation, showing details of a pair of dial-shifting vertical arms, an end view of a dial-shifting horizontal arm, and the relation of the sliding rock-shaft coupler to said arms.

75 Figures 15 and 16 are views of an operated pin-bar and carry-over mechanism, showing that the operation of said mechanism is the same for addition as it is for subtraction, Figure 15 showing the dial-wheels directly meshed with the racks for addition, and Figure 16 showing said dial-wheels meshed with the idler gears for subtraction.

80 Typewriter-keys 30 depress levers 31, forming members of trains which drive types 32 against a platen 33. The latter is mounted upon a carriage 34 having guide-rails 35 upon the typewriter-framework 31. The carriage is driven by spring 39, and moves step by step under control of an escapement-mechanism 38, which is operated in the usual manner by the keys.

85 Dial-wheels 40 at the front of the machine are rotated by means of bars 41, which extend rearwardly in parallelism and carry depressible index-pins 42, shown in my co-pending application No. 324,353, filed December 7, 1928 (now Patent No. 1,927,951, dated September 26, 1933). One pin at a time may be set in each bar, by means of the selected numeral-key-lever 31. 3 From the front of the key-lever depends a stem 45, which rocks an individual shaft 46. These shafts form members of parallel-motion linkages, one for each numeral-key. Each linkage includes a horizontal transverse pin-setting bar 48, de- 40 pressible edgewise for setting the index-pins.

90 As is disclosed in the patent to Minton 1,280,065 of September 24, 1918, and the patent to Hanson 1,278,812 of September 10, 1918, each pin-setting bar 48 is pivoted at its ends to horizontal arms or bell-cranks (not shown). Vertical arms of said bell-cranks are connected to the ends of upper transverse bars 49. Arms 56 connect the rock-shaft 46 to said bars 49, and each shaft carries at its front end an arm 62, depressible 50 by the associated key-stem 45.

95 If the register-bars 41 are in normal rearmost positions, then the indexing bars 48 may move down idly between the transverse rows of index-pins 42. However, the typewriter-carriage 34 55 operates successively denominational trains, one for each register-bar 41, to set the register-bars forward seriatim, and advance the pins 42 thereon to operative positions under the indexing cross-bars 48, as set forth in my co-pending application No. 472,610, filed August 2, 1930. A tappet 50 is settable along a rack-bar 51 of said carriage, and operates to depress seriatim vertical jointed push-rods 52, to rock bell-cranks, each of the latter having one arm 53 depressible by 52, and also 65 having a pendent arm 53a connected to one end of a shiftable coupler 54, the forward end of which coupler may strike a projection 55 formed upon the rear of the register-bar 41, to advance 70 the latter and its pins 42, bringing them properly under the indexing bars 48.

75 The couplers 54 are shiftable up and down as a set, for effecting connection and disconnection between the bell-cranks and the register-bars, 75

whereby any or all of the several registers may be brought into use.

The typewriter-carriage 34, when entering a computing zone, will cause its tappet 50 to depress the first push-rod 52, thereby operating the entire denominational train 53, 54, 41, or, in other words, bringing the register-bar 41 into operable position, with its index-pins 42 directly beneath the transverse pin-setting bars 48. At this time, the operation of any numeral-key will depress its associated transverse pin-setting bar 48, to set an index-pin 42 upon the advanced bar 41. Thereupon the key is released, and the carriage 34 escapes; whereupon the register-bar 41 is restored to normal position by means of the usual spring-device.

As the carriage steps to the next place, the push-rod 52 of the next denomination is depressed by tappet 50, and hence the next register-bar 41 is advanced, bringing its index-pins to working positions under the pin-setting bars 48.

The bell-cranks 53 are mounted upon individual rock-shafts 53^b so that the order of the denominations is transposed. There is only one set of rods 52, and this set serves all the registers. For this purpose, each rock-shaft 53^b has one arm 53^a for every register. Thus a single tappet 50 and a single rod 52 may advance bars 41 for all the registers, as explained in application 472,610. After the setting of the index-pins, the number represented thereby is run into dials 40 by means of a forward drive of the register-bars 41, which is effected by a cycling mechanism. The latter includes a power-driven general operator having a horizontal cross-bar 60, which is driven forwardly and engages the various depressed index-pins 42, and thereby carries forward the register-bars 41, to drive the dials 40 accordingly.

The cross-bar 60 of the general operator is fixed at its ends to parallel horizontal drive-racks 65, and these are guided for endwise forward and backward travel along the inner sides of side-members 66 of the framework of the computing mechanism, which is surmounted by the typewriter-framework. These side racks 65 have plates 67 to which the ends of the cross-bar 60 are attached. The side racks 65 are coupled to travel in unison by means of a cross-shaft 68, that is journaled in the side walls 66 of the base. This cross-shaft has sectors 69 fast thereon. Said sectors are connected to the racks by pinions 70.

As set forth in said co-pending application 324,353, to each dial 40 is fastened a drive-pinion 88, and these pinions may be dropped from normal idle position into mesh with drive-racks 89 that are formed upon the forward ends of the register-bars 41. After the dial-pinions 88 have become so meshed, the register-bars 41 may drive the dials forwardly for addition; but it will be understood that the pinions 88 are then withdrawn from the drive-racks 89, and remain stationary while said racks are being returned.

Said dial-pinions 88 are also used for rotating the dials 40 reversely for subtraction. For this purpose, the pinions 88 may be shifted rearwardly into mesh with idle gears 90, the latter being permanently in mesh with the racks 89, so as to advance and return therewith. The gears 90 drive the dial-pinions 88 reversely. Then the pinions 88 have to be shifted forwardly out of mesh with the idle gears 90, so that the dials may remain stationary while the idle gears 90 are being returned with the racks 89.

As set forth in said co-pending application No. 75 324,353, the dial-pinions 88, together with dials

40, are mounted upon a shiftable frame 92. The pinions are rotatable independently of one another upon an arbor 91 that forms parts of said shiftable frame; the latter also including side plates 93, in which the ends of the arbor 91 are mounted, said side plates being also joined by a cross-rod 94. The framing of the machine includes pairs of fixed guide-plates 96 rising from the cross-bar 97 of the computing base, and guiding the shiftable frames 92.

Each shiftable frame 92 is normally held up in idle position. Its front support is a horizontally-slotted arm 100, extending rearwardly from a main rock-shaft 99, that is journaled at its ends in the side members 66 of the framework, and forms part of the cycling mechanism. In the slot 101 in the arm 100 plays the cross-rod 94 of the shiftable pinion-frame.

The rear support of said frame is a fixed tie-bar 103, having on its end portions flattened collars 103^a, upon which fit horizontal slots 102 in the opposite side plates 93 of the shiftable pinion-frame. The frame therefore can slide forwardly and backwardly upon the rear collars 103^a and in the front slotted arm 100. Thus the pinions 88 may be thrust rearwardly into mesh with the idle pinions 90, and forwardly away therefrom. Said pinions rotate on the tie-rod 103.

Said shiftable pinion-frame is also capable of up-and-down swinging movement about the tie-rod 103, by rocking the shaft 99 and arm 100 downwardly, thus bringing the frame, together with its pinions, into direct engagement with the register-bar racks 89, for addition.

The rearward shifting movement of the pinion-frame 92 in the guide-slots 102, 101, may be effected by rock-arms 105, which rise from main shaft 99. These arms are loose on said shaft, and are connected by links 106 to the opposite side plates 93 of the shiftable pinion-frame, so that the rocking of the arms 105 thrusts the pinions 88 back, from normal position at Figure 2, into mesh with the idle gears 90, as at Figure 3.

It will be understood that the register-bars are cycled after the dial-pinions are shifted either down into mesh with the racks 89 or rearwardly into mesh with the idle pinions 90. It will also be understood that after the forward drive of the register-bars 41, these dial-pinions 88 are unmeshed and returned to normal free positions, where they remain stationary during the return movement of the register-bars 41.

The forward and rear reciprocation or cycling of the cross-bar 60, for operating the register-bars 41, may be effected in any suitable way, as for example by means of a handle, as shown in said Hanson Patent 1,278,812, or by a motor as shown in said Minton Patent 1,280,065, or in Hart Patent 1,171,403 of February 8, 1916, or in my pending application 324,353.

The downward movement of the addition-shifting arm 100 is effected by the main rock-shaft 99, the latter being rocked correspondingly preparatory to addition, and then reversely before the completion of the cycling of the machine.

Said main rock-shaft 99 has equipment whereby it may be coupled either to the addition-shifting arm or arms 100, or to the subtraction-shifting arm or arms 105.

This equipment is selective, and includes, upon the rock-shaft 99, a clutch-element or coupler in the form of a bail 123, having bent down arms or ears 124, which are loosely fitted upon the main rock-shaft 99. Projecting rearwardly from the bail is a lug 125, in position to engage and de-

press the addition-arm 100, or, in other words, to effect a coupling between main rock-shaft 99 and the depressible addition-arm 100. The coupler slides upon the main rock-shaft 99, being splined thereto by means of a key 126 fixed to the rock-shaft and having a groove 127 through which the coupler may slide lengthwise of the shaft, the coupler fitting in the groove, so that it must rotate with the shaft.

10 The coupler 123 may be swung to the left (see second register at Figure 11), to a position to carry the lug 125 free of the addition-arm 100, and at the same time to carry a lift-arm 128 to position beneath a horizontal bar 129, which 15 connects arms 105 and forms therewith a bail. These arms 105 have pivoted to their upper ends the links 106 with which to slide the shiftable pinion-frame rearwardly for subtraction.

10 The lift-arm 128 normally underlies a notch 130 in the bar 129, and therefore is idle whenever the coupler occupies such a longitudinal position that its depressible lug 125 registers with the depressible addition-arm 100. It will therefore be understood that whether addition or subtraction is to 25 be performed, will depend upon the point to which the coupler 123 is adjusted along the main rock-shaft 99. Said coupler may also occupy a third or neutral position when desired.

10 The different parts actuated by said main rock-shaft 99, as just described, may constitute state-controlling means for determining additive, subtractive and neutral states of the several registers, independently each of the others. This mechanism may normally be in neutral condition.

35 For fastening the keys 126 to said shaft 99, they have hubs 244. The loose arms 100 are each retained between a companion key 126 and a collar 245 fastened to said shaft 99.

40 Power for rocking the main shaft 99 of the state-setting mechanism, at the cycling of the machine, is derived from horizontal cross-shaft 133, which, at the forward stroke of the general operator (60, 65), is given a half-revolution in one direction, and at the rearward stroke of said 45 general operator is given another half-revolution in the same direction. The means for so operating shaft 133 includes two pawls and two single-toothed ratchets, and gear-trains to drive the pawls from pinions 70 that mesh with the 50 racks 65, as set forth in said co-pending application No. 324,353.

55 The main rock-shaft 99 receives its motions through an arm 155 thereon, said arm being connected by a rearward link 156 to a power-head 157, which is reciprocated by said power-shaft 133. The head 157, the link 156 and the arm 155 are driven rearwardly at the first half-revolution of shaft 133, and are driven forwardly at the second half-revolution of said shaft 133.

60 It will be appreciated that the movements of rock-shaft 99 occur before the dials are rotated by the register-racks at the cycling operation. Hence said power-head 157 is so driven by timing cams as to operate quickly the main rock-shaft 99 in advance of the rotation of the adding pinions, and to hold said main rock-shaft 99 stationary during the rotation of the dials, and then quickly to return the rock-shaft 99 in advance of the return of the register-bars 41 and their racks 65 to normal positions.

70 For these purposes, the sliding head 157 is operated by a roller-stud 158, which is driven rearwardly by cam 159 fixed on shaft 133. The stud and head are then held in normal positions 75 by a dwell-portion 160 of the cam, during oper-

ation of the register-bars 41 and pinions 88, and until the completion of the half-revolution of shaft 133. Then a companion cam 161 strikes a companion roll 162 on said head 157, and quickly drives the head forwardly to return the rock-shaft 99 to normal position ahead of the return of register-bars 41; the parts being then maintained in normal positions by a dwell-portion 163 on the cam.

10 The cams are so formed as to avoid backlash of the head 157. Said head slides partly upon a square collar 164 that is loose upon the shaft 133 and partly upon cross-shaft 68; the head having a horizontal slot at 166 to ride upon the latter.

15 From the foregoing it will be understood that when the cycling operation (set forth in application No. 324,353) has been started, and the general operator frame 60, 65 has advanced a little, and the timing shaft 133 has started to rotate, the main rock-shaft 99 is immediately 20 rocked rearwardly, thereby depressing one or more arms 100 or lifting one or more bails 129, or depressing one and lifting another, as may be determined by the operator, and accordingly shifting the pinion-frames individually either 25 backward or downward, to shift the pinions into mesh with either the idle gears 90 or the racks 89, for either subtraction or addition in the different registers selectively at the continuance of the cycling operation.

30 The main rock-shaft 99 is maintained in effective position during the forward drive of the racks 89; but at the start of the return stroke of the cycling frame 60, 65 during which the shaft 133 is driven an additional half-revolution, said shaft 133 returns the main rock-shaft 99 and its parts to normal positions, withdrawing the pinions from the gears 90 and the racks 89, so that the dials 40 remain stationary while the register-bars 41 return to normal positions at the conclusion of the cycling operation.

35 The setting of the coupler to addition, subtraction or neutral may be effected by a state-setter in the form of a slide 331, the same being a horizontal transverse plate on edge and co-operative with the coupler, the latter having a pendent lug 332 fitting in a notch 333 in the state-setter 331, so that the latter may adjust the coupler from left to right.

40 Various trains or devices are illustrated for 50 operating the state-controlling slides 331. Some of these devices are controllable by the typewriter-carriage 34, and some are controllable manually.

45 As set forth in said pending application No. 472,610, whenever the carriage advances to a point for typing any column on the work-sheet, the carriage automatically determines which register or registers are to be brought into use for accumulating the amount that is to be typed in 55 that column. After the amount is typed, it is run into the selected registers, and various parts then return to normal positions preparatory to the advance of the carriage to the next column or computing zone, whereupon the carriage again 60 determines which registers are to be brought into use.

65 The number of columns on the work-sheet is not limited by the number of registers. There may be either a single column, or two columns, or 70 any number of columns up to the capacity of the work-sheet; and the carriage at the time of typing in every column will automatically select and bring into use the necessary registers, giving different selections for different columns.

Upon the rack 51 of the carriage may be seen an adjustable dog or stop 345 which performs a number of functions. It is used for decimal tabulating of the carriage, and is also used for selecting the denominations at the indexing operations that are performed by the numeral-keys, and it is also used for selecting the register or registers that are to be brought into play in any column; and the present invention discloses certain other uses, which will appear farther on.

This dog 345 has one or more register-selecting teeth 346, each of which is set to position for depressing one of the sets of register-selecting slides 347. There is one of these slides for each one of the four registers; and the selection may be made at each column that is typed upon the sheet, that is, at each computing zone into which the carriage enters. Each dog 345 may have a tooth or teeth 346, in position to engage any one or more register-selecting slides 347. There is one dog 345 for every column on the work-sheet, and each dog has its own setting of teeth 346, and the dogs are adjustable to accord with the positions of the columns on the work-sheet, all of which is set forth in said application No. 472,610.

The register-selecting slide 347, upon being depressed, pushes down a rod 348, to depress the rear end of a bail or lever which is mounted upon a shaft 349, Figure 2. The forward arm 349^a of said lever lifts a link 350, which connects it to a bail 342, thereby raising the bail, together with the set of coupler-pins 54, to enable them to displace the register-bars 41, as already explained.

At this point there is performed a novel function of said carriage-dog 345, inasmuch as the raising of the bail 342 operates to lift a latch 335, which hooks over said bail at 343. There is one of these latches for every bail 342. The lifting of the latch 335 withdraws it from a notch 336, with the result that the machine is set for addition in the register that is selected. Hence, at every column or computing zone, addition can be effected in the selected register or registers, according to the raising of the latches 335, whose control over the setting of the dial-pinions will presently be explained, as will also the manner whereby the latches are returned to normal positions, preparatory to selected release thereof in the next computing zone.

Each latch 335 normally holds back a forwardly-extending rod 337, which is urged forwardly by a spring 338, and carries at its front end a cam-head 339. This head has a composite cam 340, to engage a lug 341 which projects from the bottom edge of the state-setting slide 331. This moves said slide and causes it to thrust the coupler 123 along the main rock-shaft 99 to addition-position, as shown at the first and third cam-heads 339 at Figure 6. There is one of the rods 337 (and one of the latches 335) for each of the four registers 40. The latches 335 are selectively withdrawn every time by the typewriter-carriage, as the latter enters successive computing zones; the carriage causing the bail 342 to lift the coupler-pins 54 from normal position of disuse at Figure 2 to the position of use shown for the two right-hand bails at Figure 6.

The latch 335 being thus raised by the bail 342 of the carriage-selected register, the rod 337 steps forward, as explained, for setting the selected register mechanism to addition; the lug 125 being thus brought over the depressible arm 100, so that when the main rock-shaft 99 is rocked during the cycling operation, said lug 125 depresses the arm 100 and engages the pinions 88

directly with the racks 89, for the performance of addition at the next cycling stage.

It will be understood that the lifting of a latch 335 by means of a bail 342 permits the spring 338 to pull the cam-head 339 forwardly enough to cause the state-setting slide 331 to be moved towards the right by the addition-cam 351. All cams terminate in dwell-portions, so that the state-setting slides or heads 331 are locked against accidental displacement in all positions.

The state-setter 331 and the coupler 123 may be set to subtraction by the aid of a subtraction-key 334, Figures 1 and 6, at the front of the machine.

Between the subtraction-key and the state-setter 331 works a train that co-operates with the key and with the state-setter, and also with the carriage 34 of the typewriter.

The cam-rods 337 have normally limited forward motion, because longitudinal slots 352 in their rear ends are partly occupied lengthwise by rear stops 353. These rear stops 353, however, may be withdrawn by the subtraction-key 334, which rocks a cross-shaft 354 having arms 355 to which are pivoted the upper ends of the rear stops 353, so that the latter may be all withdrawn at the operation of the subtraction-key. The springs 338 may therefore give the rods 337 full forward strokes. Each rod and cam-head 339 therefore first shifts the state-setter 331 idly towards the right, and then shifts it to its extreme leftward position, and then locks it by means of the dwell-portion of the slot. At this time, the subtraction-finger 128 of the coupler extends beneath the subtraction-bail 129, thereby coupling the latter to the main rock-shaft 99, for the purpose of thrusting back the pinion-frame 92 to mesh the pinions with the idle gears 90, to effect subtraction during the cycling operation.

The subtraction-key 334 is shown at Figure 1 in its operated rear position, having tensioned its return spring 356. The rear end of the key-stem has vibrated a lever 357, and the latter has operated upon rock-arm 358 upon the transverse shaft 354, to raise all of the rear stops 353 connected to said shaft. A latch 359 engages another arm 360 to maintain the parts (Figure 1) in set positions.

From the foregoing, it will be seen that operation of the key 334, as at Figure 1, will withdraw all of the rear latches 335, thus leaving the cam-rods 337 under the domination of the springs 338 and the several register latches 335, so that whenever the paper-carriage calls any register into use, its latch 335 will be raised and thereby release the cam-rod 337 for movement to its extreme forward or subtraction position, with a pin 361 standing in rear of a bar 361^a, Figure 6, which is used for restoring the rods 331.

As it may still be desired to add certain amounts in some registers, there is provided for each of the registers a manual state-controller. This has the form of a key 362 provided upon the forward end of a horizontally swinging lever 363, and having a tooth 365 to enter any of the notches 366 in a plate 367, Figures 2, 4 and 11, provided upon the front of a fixed bracket 368, Figure 4. At its rear end said lever 363 is loosely pivoted by bent fingers 369 in a stop-arm 370, the latter being pivoted at 371 upon the top portion of the bracket 368, the left end of said lever carrying a stop 372 into the path of the cam-head 339, to intercept the latter, as it is being pulled forward by its spring 338. The point of arrest of the cam-head depends upon which of the notches 75

366 is being occupied by the detent 365, as determined by the setting of the selective state-selecting key 362. There are three of said notches, so that said key can be positioned for either neutral, addition or subtraction, thus setting stop 372 at any one of three arresting positions.

If the key 362 is adjusted to the extreme right, then its stop 372 occupies the extreme forward position, as seen near the left in Figure 11, and hence the cam-head and rod are permitted to make a full forward stroke when the paper-carriage releases the latch 335. The composite cam 351, during such full stroke, vibrates the state-setting slide 331 first idly to the right, and then to the left, with the tooth 341 occupying the dwell or lock portion at the inner end of the cam, as seen at the lower right-hand corner of Figure 6. By this movement, the coupler 123 will be shifted to the extreme left, with the lifting finger 128 in effective position beneath the subtraction bail 129, so that the latter, during the ensuing cycling operation, will thrust back the links 106 and the pinion-frame 92, to mesh the pinions with the idle or subtraction gears 90, as seen at the middle portion of Figure 11.

If, however, the state-selecting key 362 is set to midway position, then its stop 372 will be held in a midway position, as seen at the extreme left of Figure 6, so that the rod 337 and its cam-head 339 will be intercepted by the stop 372 by the time that the cam has thrust the state-setting slide 331 to the right; and in this position the slide 331 is locked by the midway dwell in the cam 340. At this time, the coupler 123 is in the extreme right-hand position, with the subtraction-finger 128 occupying an idle position under the notch 130 in the subtraction bail 129, and the lug 125 is overlying the addition-arm 100, as will be evident from Figure 4. Thus, at the next 40 cycling operation, the rocking of the main shaft 99 will depress said addition-arm 100, to carry down the pinion-frame 92, bringing the pinions into direct mesh with the drive racks 89, Figure 12.

45 There is one state-selecting key 362 for every register, and it will be understood that, for some work, these may be all set as required at the beginning of the typing of a page of computation; and that, whenever required during the 50 typing of the page, the setting of any key may be varied to cause subtraction of an amount in an addition column, or vice versa, or to prevent computation of an amount which is typed in a column, or to cause computation of an amount in a neutral column.

If the operator sets a front state-selecting key 362 to subtraction, and then operates the general subtraction-key 334, the selected register will be conditioned for subtraction. If, however, the operator chooses to first press the general subtraction-key 334, any selected register will become conditioned for subtraction as soon as the selecting key 362 therefor is set for subtraction. It will be understood that where the subtraction-key 334 is the first to be operated, the parts operated thereby are latched by 359, to permit a state-selecting key 362 to be set to subtraction, whereby the register will be conditioned for subtraction.

70 The latch 359 having done its work may as well be released, and according to one feature of the present invention the beginning of the forward stroke of the general operator may be utilized for 75 automatically releasing this latch 359, and it is

held released until the latched parts have returned to their normal positions.

In one of the side bars 65 of the general operator, there is therefore provided a notch 281 to be normally occupied by a roll 282, carried by a lever 283, which is rocked when the general operator side bar 65 forces the roll out of the notch. A pin 284 on the lever lifts a cam 285 on the latch 359, thereby releasing the arm 360 and the rock-shaft 354, which is returned to normal position by a spring 286. The rear latches are thus permitted to drop into the notches 352 when the rods 337 are returned. The roll 282 may run idly upon the edge of the bar 65; but upon the completion of the return stroke of the general operator a spring 373 forces the roll 282 back into notch 281, in readiness for the next unlatching operation.

It has already been explained that the shaft 133 is given half a revolution at the forward stroke of the general operator, and an additional half a revolution on the return stroke of the general operator, for the purpose of operating the mechanism which shifts the dial-pinions to addition or subtraction position. The same shaft 133 is also used for restoring to normal positions the rods 337, and their cams 339, this restoration taking place after every computation.

Upon the one-revolution shaft 133 are cams 374, which raise rollers 375 that are pivoted upon bell-cranks having pendent arms 376, which thrust rearwardly links 377, the latter being fastened at their rear ends to cross-bar 361^a, which is universal to the cam-rolls 337. This universal bar 361^a sweeps rearwardly and picks up all of the pins 361 upon said cam-rods, and thereby presses all of the latter rearwardly to normal positions, permitting the addition-controlling latches 335 to be moved down into their notches 336 by means of springs 378, Figure 2, preparatory to the next computation. Said springs 378 also pull down the several register-bails 342 and rock the arms 349^a. Spring 286 also thrusts the rear or subtraction latches 353 down into their notches 352, thus bringing about the completion 45 of the compute cycle.

Provision is also made for automatic means for enabling the carriage to predetermine the additive, subtractive or neutral state of each register in each of the typed columns. It has already been described that by means of a tooth 346 that is set in an adjustable carriage-dog 345, the carriage 34 is enabled, when computing in each column on the work-sheet, to predetermine into which register or registers the typed amount shall be entered. There may be only one tooth 346, as shown at Figure 2, or there may be two teeth, or there may be one for every register. Thus, irrespective of the number of columns on the work-sheet, it is automatically determined by the carriage into which registers each amount will be entered. For example, the separate amounts typed in one line in each of ten different columns may all be entered in one register, thus giving cross-addition. As another example, every amount that is typed in the first three columns may be run into one register, and every amount written that is typed in the next three columns may be entered into the second register, and every amount written in the next three columns may be entered into the third register, and every amount written in the last three columns may be entered into the fourth register, thus giving quadruple cross-addition. Or every 75

amount that is typed in one column may be entered in only one register, thus giving vertical addition; while amounts written in other columns may be cross-added; and one register may also be reserved for securing a grand total of all computations.

It will be remembered that when any of the selected balls 342 is lifted by the action of a cam-tooth 346 on the carriage, the addition-latch 10 335 is lifted by said ball and is withdrawn from the notch 336 in the cam-rod 337, so that the spring 338 may pull forward the cam-rod to addition position; but the rod is stopped at this point by the rear latch 353, which remains in 15 the notch.

Provision is also made whereby the carriage may withdraw all the rear latches 353, to set the machine automatically for subtraction.

Set into said carriage-dog 345 there is shown 20 at Figure 2 a special subtraction-tooth 380, Figure 7, which operates a special subtraction-plate 379, similar to 347. Plate 379, when depressed by tooth 380, presses down a rod 381 that resembles 348, but is twisted at its lower end and pivoted to a crank-arm 382 on rock-shaft 383, which has an arm 384, Figure 7, to which is pivoted the inner end of a horizontal latch 385. This latch is therefore withdrawn by the action of the carriage on the plate 379, and permits a bell-crank 30 386 to be rocked about its pivot 387 by means of a spring 388. A pin 389 on said bell-crank operates a cam-arm 390 upon the shaft 354, to rock the latter in a manner to lift all the subtraction-latches 353 up out of the notches 352 in their 35 cam-rods 337. Said latches are held up as long as the cam-tooth 380 on the carriage holds down the subtraction-slide 379, that is, during the entire typing of an amount in the column on the work-sheet.

40 It will be seen that when the subtraction-shaft 354 is rocked by the subtraction cam-tooth 380, the same result is gained as when said shaft is rocked by the general subtraction-key 334; the shaft 354 in each case becomes detained by the latch 359, prior to the initial movement of the cycling mechanism. However, the latch 359 may be idle so long as the carriage-tooth 380 is holding down the subtraction-plate 379, but it is useful when the key 334 is brought into use for 45 setting to subtraction.

From the foregoing it will be seen that at every column, that is in every computing zone, regardless of the number of registers, the carriage determines in how many and which registers computation is to take place, and it is also automatically determined that they shall all operate additively, unless there has been provided in the dog 50 345 for that zone a subtraction cam-tooth 380, to operate the subtraction-plate 379, in which case the amount written in that column will be run subtractively into every selected register, providing that the various keys 362 occupy subtraction positions. It will also be perceived that 55 regardless of the setting of 362 to subtraction, addition will be performed if the subtraction-tooth 380 is omitted for that zone.

It will be seen that when the spring 388 pulls down the arm 386, the latter is arrested by a stop 391, with the arm 386 lying in the path of the 60 withdrawn latch 385, so that the latter cannot be restored by its spring 392 when the carriage-controlled plate 379 is to be lifted. However, when cross-bar 60 of the general operator travels forwardly, it engages a cam 393 on an arm 394 65 forwardly, it engages a cam 393 on an arm 394 of the bell-crank lever 386, and forces said lever 70 75

to vibrate, thereby lifting the arm 386 up out of the path of latch 385, so that the latter may be restored to the right by the spring 392, Figure 7, while the spring 388 holds the arm 386 down upon said latch 385, thus bringing the plate 379 5 to position to be operated by the cam-tooth 380 upon the succeeding carriage-dog 345.

If it is desired that in any zone or column position neither addition nor subtraction shall be performed in any register or registers, the cam-tooth 346 may be omitted from the dog 345 for 10 that zone, so that the balls 342 will not be elevated, and motion of the coupling pins 54 will be idle.

If, during the time when the state of the 15 computing mechanism is being controlled automatically by the carriage, it should be desired to prevent an amount from being run into any register, then key 362 for said register may be shifted to neutral position. The arm 372 will 20 occupy the rearmost dotted-line position at Figure 11, thus preventing the cam-rod from being advanced from its normal neutral position. The key 362 is capable of forcibly returning its cam-rod to rearmost position. The key 362 may then 25 be reset to subtraction. All of these keys may stand idly at subtraction when the state of the computing mechanism is being dominated by the carriage.

As the carriage enters each zone, it is automatically determined which totalizers are to operate, and whether each one is to add or subtract. The setting is again effected for every column on the work-sheet, that is, for every 30 computing zone. The keys 362 are for the registers, not for the columns.

Connected to each bar 337 is a signal 395, which is visible through a sight-opening 396 in the casing of the machine, and has a vertical arbor 397, provided at its lower end with a 40 crank-arm 398, having a wrist-pin 399 connected by a link 412, Figure 8, to the cam-bar 337. The cam-bar will thus rock the arm 388 and the signal 395, to indicate whether the register is set for addition, subtraction or neutral; this 45 indication being independent of the setting of the key 362. All of the keys 362 may in some instances be set for subtraction, while, in fact, either addition, subtraction or neutral may be the rule for certain registers in certain columns; 50 so the operator need not consult the keys 362, but will be governed by the signals 395.

The usual key 400 that operates a clearance-printing mechanism is the same type as is disclosed in the patent to Hoyt, 1,256,309, of February 12, 1918. Feelers 401, Figure 5, may fall into a row of deep notches 402 in the adding pinions 88, and the ball 403, which normally locks the star-key 400, may be withdrawn to a key-releasing position by spring 404. The ball 60 swings back out of the path of a nose 405 on the top of key-shank 406.

The gang of adding wheels and dials is movable from normal position, either rearwardly or downwardly, and such movement is governed by 65 the state-setting slides 331, one of which is shown at midway position at Figure 5, with a notch 407 in register with a shoulder 408 on the key, thus affording a clearance to permit the key to be depressed. The ball 403 is mounted 70 upon the movable dial-frame 92, so as to move backwardly or downwardly therewith; but at such times the star-printing key 400 is inoperable, because the notch 407 will be out of register with the locking shoulder 408 on the key-shank. 75

Hence, said key can be depressed only when the nose 405 and bail 403 are out of co-operative relation, as shown at Figure 5, and when all of the feelers 401 occupy the large notches 402 in the wheels.

The further advantage is gained by the novel star-key construction, in that when the general operator or cycling mechanism is called into operation by the star-key, it might happen that 10 an index-pin 42 stands depressed, and consequently its register-bar 41 will be advanced by the general operator at 60. The number represented by said pin, however, is not carried into the register, since the latter must stand in normal neutral position (Figure 5) before the star-key 400 can be depressed and cause the general operator to cycle. Hence, no number can be run into the register at this time, even though a pin 42 remains depressed. The star-key has 15 the usual stem 409, to operate the usual arm 410 and shaft 411, to control the printing of the star-type and to bring the general operator into action.

Figures 15 and 16 show details of the carrying mechanism which operates on the pin-bars 41 to effect extra carrying steps of the same beyond the advance effected by the forward stroke of the general-operator cross-bar 60. Inasmuch as said mechanism is fully described in the aforesaid application No. 601,173, the following brief description is given to indicate generally the operation of said mechanism.

Each dial-wheel 40 has a carrying tooth 175, which, in the rotation of the wheel to or past its zero-position, rocks a lever 176 to raise the forward end of an elongate latch 177 normally latched over a bar 178. Said latch thus raised escapes from said bar 178, and pulled by a spring 179 moves forwardly to rock a lever 180, fulcrumed on a rod 181 and pivotally attached to said latch at 182. Said rocked lever 180, provided with a stud 183, will thus have moved said stud rearwardly from its normal position to intercept a downwardly-extending arm 184 of a lever 185, fulcrumed on the general-operator cross-bar 60 at 186, and rock said lever 185, to thereby move a finger 187 thereof forwardly as the cross-bar 60 completes its forward stroke.

Forward movement of the latch 177 is limited 50 by abutment of its attached lever 180 with a rod 188. When no carrying operation takes place, the lever 185 is in the position seen in Figure 3, wherein its finger 187 abuts the general-operator cross-bar 60 upon engagement of said finger with a depressed index-pin 42. It will be understood also that when no carrying operation takes place and when the general operator 60 is at the end of its forward stroke, the arm 184 of the lever 185 will just abut the stud 183, which, 55 with the latch 177 caught over the bar 178, will be in its normal forward position. For each dial-wheel 40 from which a carrying transfer is to be made to the wheel of next higher denomination, there extends one of the carrying trains 60 just described. Each latch 177 has a rearward extension 189 which serves as an overthrow stop for the pin-bar 41, as will be evident from Figures 3, 15 and 16, wherein it is shown that the depressed pin 42 is held between the finger 187 and said extension 189 as the cross-bar 60 reaches 65 the end of its forward movement. The latch-bar 178 is moved forwardly, whereupon the escaped latches 177 will again be caught thereon, said forward movement taking place during the re- 70 turn stroke of the cross-bar 60, inasmuch as all 75

the carrying operations precede said return stroke. During the denominational selection of the pin-bars 41 as effected by the carriage, the latch-bar 178 remains in such position that there is enough room between the extensions 189 and the first index-pin 42, which, as shown in said application No. 601,173, is the zero-pin, and which is normally depressed, said zero-pin becoming automatically raised upon depression of a higher pin. At the beginning of a cycling 10 operation, the latch-bar 178 of each register, with all the latches caught thereon, is moved rearwardly, thereby bringing the extensions 189 rearwardly, so that the front faces of the depressed zero-pins just touch said extensions. For 15 moving the several latch-bars 178, the general-operator cross-shaft 68 is employed and accordingly carries a pair of cams 190 to operate slides 191, to which said latch-bars 178 are operatively connected. 20

At the end of each computing cycle restoration of all the depressed significant pins 42 is effected by operation of a universal bail (not shown), provided for each set of pin-bars and operating to reset all the zero-pins in the manner 25 set forth in application No. 324,353.

It will be seen from Figure 2 that the universal bar 361^a that restores the cam-rods 337 has advanced forwardly again before the end of the computing cycle and after having restored said 30 cam-rods. This permits said cam-rods 337 to assume their carriage-selected state-determining positions as soon as the carriage enters a computing zone. The cams 374 are formed and timed 35 accordingly. To secure non-skewing movement of the universal bar 361^a, there are provided two of said cams 374 and corresponding arms 376, each of the latter being pivotally mounted upon two of the fixed dial-frame guide-plates 96 that rise from the framework of the machine. The 40 universal member 361^a rests upon the cam-rods 337 and is retained laterally and against upward displacement by headed shoulder-screws 195 in its ends which abut the outer edges of the outer cam-bars 337. Each of the links 371, connected 45 to said universal bar 361^a, is urged forwardly by a spring 196, which also serves to keep the cam-roll 375 at all times against its cam 374. The forward end of said spring may be anchored to the cross-member 97 of the framework, Figure 2. 50

The upper ends of the addition-latches 335 may be retained in slotted guides 197, Figure 2, fastened to comb-plates 198, in which the rear ends of the pin-bars 41 are spaced and guided, said comb-plates having openings 199, Figure 6, 55 which afford clearances for the ends of the couplers 54, and the lower edges of which limit the downward movements of the latches 335, the latter being provided with projections 200 which may abut said edges. At their lower ends the addition-latches 335 and also the subtraction-latches 353 are guided and retained in pairs in plates 201, Figures 2 and 6, said plates abutting bosses formed on the bottom of a rear cross-member 202 of the framework. The corresponding cam-rod 337 may closely underlie each plate 60 201, Figure 10, and may be supported by headed shoulder-screws 203, which secure said plate 201 to the cross-member 202, and whose shoulders and heads abut the side edges of the cam-rod 65 337 to retain the latter. 70

The transverse subtraction-shaft 354 may have a stop-arm 204, Figure 6, to limit its latch-withdrawing rotation by abutting with one of the comb-plates 198. A center bearing 205 for said 75

subtraction-shaft 354 may rise from said combination. Downward movement of the subtraction-latches 353 may be limited by pins 206 projecting from the sides of said latches for abutment with the plates 201. The short shaft 383, whereby movement of the subtraction-rod 381 is transmitted to the horizontal latch 385, may be journaled in a bracket 207, secured to the top of the framework cross-member 202 and formed as best seen in Figures 2 and 7.

Spanning the front of the framework cross-member 97 is the angle bar or bracket 368, secured at its front ends to said member by screws 210. To the front face of said bracket the notched plates 367 for locating the manual state-setting levers in their different positions are secured by screws 211. Each lever 363, articulated with the stop-arm 370, may be yieldably held against the saw-tooth station notches of its plate 367 by a spring 209, Figure 4, which may be anchored to said bracket 368.

The cross-member 97 has near its ends forwardly-extending bosses 212, from the front faces of which there is spaced, by collars 213, a plate 214, which spans the pair of said bosses 212 to slidably support the several state-setting slides 331. The latter have slots 215, the outer slots of the slides for the outer registers slidably fitting said collars 213, Figure 4. The other slots 215 of the several slides 331 may fit over collars 216 retained by broad headed screws 217 against the plate 214, said screws also slidably retaining the slides 331 against said plate, Figure 11.

Intermediate bosses 218 extending from cross-member 97 may embrace the plate 214. Said plate 214 also has slots 219 for slidably supporting the front ends of the cam-rods 337, said slots fitting the cam-heads 339 of said rods.

Each dial-frame - subtraction - shifting ball 40 formed by the arms 105 and bar 129 is retained lengthwise on the rock-shaft 99 by the key 126, which, it will be remembered, is fastened to said rock-shaft. Said key 126 has a tongue 220 fitting and normally abutting the bottom of a slot 221 in the bail-bar 129. Said tongue thus also serves to reverse the bail when the dials 40 are to be shifted forwardly to unmesh them from the idle gears 90. The left arm 105 of each bail has a tongue 222, which registers with a clearance slot 223 in the state-setting slide 331 when the latter is set at subtraction, said slot then permitting operation of the bail as seen at the right-hand register in Figure 11. With the state-setting slide at neutral, as seen at the left-hand register, Figure 11, the bail is locked by abutment of its tongue 222 with the top edge of the slide 331. Said edge may, if desired, be extended to the left to also lock the bail during addition. This extension is deemed unnecessary, however, inasmuch as shoulder-screws 224, which secure the dial-arbor 91 to the dial-shifting frame 92, and which project beyond the sides of said frame, enter vertical notches 225 in the outer guide-plates 96 of said frame during addition. Said notches thus prevent rearward displacement of the frame during addition. Similarly, horizontal notches 226 embrace the shoulder-screws 224 when the dial-frame is shifted rearwardly to mesh with the idle gears 90 for subtraction and prevent downward displacement of said frame while the dials are so meshed. The notches 225, 226 may be open as indicated in the drawings, in order to facilitate removal and replacement of the computing-pinion frame

92, the slots 102 of the latter being also open for this purpose.

With the machine at normal, the dial-frames are upheld by studs 227 which project from the keys 126 that are fastened to the rock-shaft 99, 5 said studs abutting the lower edges of the dial-frame-shifting addition-arms 100. Said studs 227 also serve to enable said keys 126 to swing said arms 100 reversely when the dial-pinions 40 are to be unmeshed from the racks 89. When 10 the rock-shaft 99 is actuated to mesh the dials 40 for subtraction, the studs 227, being on the keys 126 that are fastened to said rock-shaft, recede from the arms 100. For upholding the dial-wheel frames until their shoulder-studs 224 15 are properly within the notches 226, there are provided springs 229, Figure 11, one at each side of each frame 92. The lower end of each spring 229 is attached to a stud 230, which normally abuts a piece 231 to limit upward movement of the frame and which is adjustably fastened to the side plate 96 by a screw 232. Said piece 231 has a lug 233, to which the upper end of the spring 229 is anchored. Another lug 234 abuts the front edge of the plate 96 to prevent 25 rotation of the piece 231 when the screw 232 is loosened.

Each vertical signal-arbor 397 may be journaled in a bracket 236, Figure 8, which may be secured to the plate 214. 30

The spring 286 coiled around the subtraction-cross-shaft 354 has one end anchored to a collar 240 fastened to said shaft. The other end of said spring reacts against an arm 241 loose on said shaft which, in turn, reacts against the pin 35 389 of the bell-crank 386, which, it will be remembered, is released by the carriage to rock said shaft to withdraw the subtraction-stops 353 for releasing cam-rods 337.

It will be seen from Figure 3 that said bell-crank 386 is restored by the general operator before said cam-rods 337 are restored. Consequently, the loose arm 241 is displaced and the tension of said spring 286 becomes potentially effective to rotate the shaft 354 inasmuch as in 45 the restoration of said bell-crank 386, its pin 389 has reached from the cam-arm 390. Thus, as soon as cam-rods 337 are restored, the latches 353 will re-enter the notches 352 under the influence of said spring 286. By this arrangement 50 said spring 286 does not oppose the spring 388 when the latter rotates the bell-crank. As shown in Figure 6, the loose arm 241 may be retained between the cam-arm 390 and a block 342 fastened to said shaft and separated from 55 said arm 390 by the spacer 243, said block and collar being omitted from Figures 2, 3 and 9 for clearness.

Variations may be resorted to within the scope of the invention, and portions of the improvements may be used without others. 60

Having thus described my invention, I claim:

1. In a computing machine, the combination with a set of computing pinions, drive-racks therefor, a set of idlers meshed with said racks, 65 a general operator, and a carriage, of means to selectively mesh the computing pinions to the racks or idlers during the cycling of the general operator, a releasable spring-pressed state-controller for said meshing means, means controlled by said carriage to release said controller to different extents to predetermine whether the pinions are to be meshed with the racks or idlers, and manually-operable means for effecting a shift of said controller, before the cycling opera- 70 75

tion, to a position other than the one determined by said carriage.

2. In a computing machine, the combination with a set of computing pinions, actuators therefor, said pinions normally disengaged from said actuators, the latter being arranged to perform addition or subtraction, a carriage and cycling mechanism, of a state-controller releasable to different positions to determine adding or subtracting engagement of said pinions, means controlled by said carriage to release said controller, said controller and releasing means arranged so that said controller may assume its selected state-determining position as soon as the carriage enters a computing zone and before operation of the cycling mechanism, and means connected to said cycling mechanism to restore said controller, said restoring means timed to recede from said controller, after having restored the same, to permit said controller to assume a subsequent state-determining position as soon as the carriage enters another computing zone.

3. In a computing machine, the combination with a set of computing pinions and actuators therefor, arranged to perform addition or subtraction, said pinions normally disengaged from said actuators, of a spring-pressed state-controller for determining adding and subtracting engagement of said pinions, a pair of latches, one of which normally holds said controller in neutral position, said latches arranged so that the withdrawal of said one latch will permit said controller to assume an adding position and so that the releasing of both latches will permit said controller to assume a subtracting position, and means for restoring said controller.

4. In a computing machine, the combination with a plurality of sets of computing pinions and sets of actuators therefor, arranged for addition or subtraction, said pinions normally disengaged from said actuators, of a spring-pressed state-controller individual to each set of pinions for determining adding or subtracting engagement of said pinions, a pair of latches for each controller, one of said latches normally holding the controller in neutral position, said latches arranged so that the withdrawal of said one latch permits said controller to assume an adding position against the other latch, the withdrawal of both latches permitting said controller to assume a subtracting position, means whereby the carriage as it enters a computing zone withdraws the addition-latches selectively, and manually-operable means whereby the several subtraction-latches are withdrawn simultaneously.

5. In a computing machine, the combination with a plurality of sets of computing pinions and sets of actuators therefor, arranged for addition or subtraction, said pinions normally disengaged from said actuators, of a spring-pressed state-controller individual to each set of pinions for determining adding or subtracting engagement of said pinions, a pair of latches for each controller, one of said latches normally holding the controller in neutral position, said latches arranged so that the withdrawal of said one latch permits said controller to assume an adding position against the other latch, the withdrawal of both latches permitting said controller to assume a subtracting position, means whereby the carriage as it enters a computing zone withdraws the addition-latches selectively, and means controlled by said carriage whereby all the subtraction-latches are withdrawn simultaneously, thereby causing the controllers whose adding

latches have been released to assume subtracting positions.

6. In a computing machine, the combination of a set of dial-wheels, actuators for said dial-wheels, said wheels normally disengaged from said actuators, a member spanning said wheels and controlled thereby to assume one position when all the wheels stand at zero and another position when one or more wheels are not at zero, a key locked by said member when the latter is in said other position, said key operable when said member is in the first-mentioned position, a frame in which said wheels and member are mounted, and means for shifting said frame to engage the wheels with the actuators, said frame including a shifter connected to said frame, said shifter arranged to lock said key when the frame is shifted to engage the dial-wheels with the actuators.

7. The combination of a general operator, a plurality of sets of drive-racks operable thereby, each set having indexing mechanism, a set of idlers connected to each set of drive-racks, a plurality of sets of computing pinions normally out of mesh with racks and idlers, either set of pinions being shiftable into mesh with either its associated racks or its associated idlers independently of the other set of pinions, to cause the advance of said racks by said general operator to effect addition in one set of pinions and simultaneous subtraction in another set of pinions, or to cause simultaneous addition in both sets of pinions or simultaneous direct subtraction in both sets, and common means for selectively shifting said pinions and for returning the same to normal position.

8. The combination of a general operator, a plurality of sets of drive-racks operable thereby, each set having indexing mechanism, a set of idlers connected to each set of drive-racks, a plurality of sets of computing pinions normally out of mesh with racks and idlers, and differentially adjustable means controllable by said general operator through the medium of a common rotary shaft and connecting train for transversely shifting each set of said pinions independently of the other set of pinions into mesh with either said drive-racks or said idlers.

9. In a computing machine having a letter-feeding carriage and carriage-operated denomination-selecting trains, the combination of a set of computing pinions, indexable drivers therefor, a carriage-controlled device for coupling said denomination-selecting trains to said drivers preparatory to the entrance of the carriage into a computing zone, a general operator for said drivers, means, selectively conditionable for operation by said general operator, for connecting said pinions and drivers in different ways for different computing states, a spring-pressed computing-state controller shiftable for conditioning said pinion and driver connecting means, and a latch restraining said state-controller, said latch being releasable by said carriage through said coupling device.

10. In a computing machine having a letter-feeding carriage and carriage-operated denomination-selecting trains, the combination of a set of computing pinions, indexable drivers therefor, a carriage-controlled device for coupling said denomination-selecting trains to said drivers preparatory to the entrance of the carriage into a computing zone, a general operator for said drivers, means, selectively conditionable for operation by said general operator, for connecting

said pinions and drivers in different ways for different computing states, a spring-pressed computing-state controller shiftable different extents for selectively conditioning said pinion and driver connecting means, a latch restraining said state-controller, said latch being releasable by said carriage through said coupling device, and a stop coacting with said state-controller upon release of said latch to determine one of the computing states.

11. Machine constructed according to claim 10, in which said stop is removable at will in conjunction with the release of said latch, to enable said state-controller to determine a different computing state.

12. Machine constructed according to claim 10 having means controlled by said carriage, for withdrawing said stop in conjunction with the release of the latch thereby to determine a different computing state.

13. In a combined typewriting and computing machine having a plurality of registers, a letter-feeding carriage and a carriage-operated trunk-set of denomination-selecting trains ramifying to the several registers, the combination of a plurality of sets of computing pinions, a plurality of sets of individually indexable drivers therefor operative to drive the pinions reversibly, individual carriage-controlled devices for selectively coupling the sets of drivers to corresponding branches of the denomination-selecting trains, a general operator for said drivers, individual controlling means associated with each set of computing pinions, selectively co-operable with the general operator, for determining engagement with the drivers and the direction of driving of the computing pinions, an individual spring-pressed state-controller being associated with each set of computing pinions and its said controlling means, an individual latch for restraining each state-controller, the several latches being connected so as to be selectively releasable by the carriage, by means of said carriage-controlled coupling devices, and a stop coacting with each state-controller upon the release of its latch to determine one of the computing states.

14. Machine constructed according to claim 13 in which each state-controller when restrained by the latch determines non-co-operation of said controlling means with the general operator, to determine non-engagement of the associated computing pinions with their drivers during the general-operator cycle; said stop upon release of the latch by means of the corresponding carriage-controlled coupling device, limiting the resulting state-controller shift to determine additive driving of the pinions; said stop being releasable to permit further shift of the state-controller to reverse the pinions.

15. In a computing machine having a set of computing wheels, the combination with a set of racks and idlers meshing with the racks, for driving the wheels reversely, and a general operator for advancing and returning the racks, of mechanism whereby the general operator may shift the pinions in relatively transverse directions for engagement with either the racks or the idlers, said mechanism including a shaft operable by the general operator to rock intermittent-ly in opposite directions prior, respectively, to the advance and return of the racks, two pinion-shifters individually loose on said shaft, a clutch-element splined to said shaft to separately engage either shifter, and a movable mounting for said pinions arranged and connected to said

shifters, to shift the pinions in either direction, dependent upon which shifter is clutched to said shaft.

16. Machine constructed according to claim 15, the mounting including a frame having the computing pinions at the front thereof, the shaft extending crosswise in front of said frame, the racks being under, and the idlers being behind, the pinions, one of the rockable shifters extending horizontally from the shaft and being operatively connected to the front part of the frame, the connection being arranged to also support the frame at its front for free rearward and forward movement effected by rocking of the other shifter, the latter extending vertically from the shaft, said frame being supported at its rear for said horizontal movement, the rear support also forming a pivoting device about which the frame is swung toward and from the racks by the rocking of said horizontal shifter, the vertical shifter having a connection to said frame arranged to freely permit said swing.

17. Machine constructed according to claim 15 and including a state-determining member movable transversely of said shaft and having a cam, and an intermediate member mounted for movement parallel to said shaft and articulated to the clutch-element so as to permit rocking of the latter, said intermediate member enabling the state-determining member, by means of its cam, which engages said intermediate member, to set the rockable clutch-element.

18. In a computing machine having a carriage, the combination with a set of computing pinions, drivers for driving the pinions in one direction for addition, and in reverse direction for subtraction, and a general operator for the drivers, of a spring-driven differentially-movable state-determining member, means controlled by the differential movement of said member, for enabling the general operator to connect the pinions and drivers for driving the pinions reversibly, latching means restraining said member and differentially operable by the carriage as it enters a computing zone to release said member, the latter arranged to respond to said release by immediate movement of an extent dependent on the kind of computation repeatedly effected in said zone, and means manually settable to limit said movement to a less extent than is determined by said carriage, thereby to effect another kind of computation at will.

19. In a computing machine having a carriage, the combination with a set of computing pinions, drivers for driving the pinions in one direction for addition, and in reverse direction for subtraction, and a general operator for the drivers, of a spring-driven differentially-movable state-determining member, means controlled by the differential movement of said member for enabling the general operator to connect the pinions and drivers for driving the pinions reversibly, latching means restraining said state-determining member and differentially operable by the carriage as it enters a computing zone to release said member, and means co-operative with the general operator for restoring said state-determining member, said restoring means being arranged so that after the restoring operation it is clear of said state-determining member, so that the latter may respond to its carriage effected release by immediate movement of an extent dependent upon the kind of computation effected in a zone.

20. In a computing machine having a carriage,

the combination with a plurality of sets of computing pinions and drivers therefor, and a general operator for the drivers, of selectively conditionable means for each set of pinions and 5 operative with the general operator for connecting said pinions and their drivers for adding or subtracting, a spring-driven state-determining member for each set of pinions for conditioning said means, a pair of latches for each state-de-10 terminating member, one of said latches normally holding said member in neutral position, each pair of latches arranged so that release of said one latch permits said state-determining member to assume an adding position against the 15 other latch and so that the release of both latches permits said state-determining member to assume a subtracting position, means whereby the carriage as it enters a computing zone releases the adding latches selectively, and subtraction-20 setting means operable manually or by the carriage and connected to release all the subtraction-latches, thereby to cause all the state-determining members, whose adding latches have been released by the carriage, to assume subtracting 25 positions.

21. In a computing machine having a carriage movable to different computing zones, the combination with a set of computing pinions and drivers therefor, of a spring-driven state-deter-30 mining member operable to determine connection of said pinions and drivers for reversible driving of the pinions, a latch normally restraining said member in neutral position determinative of non-connection of said pinions and driv-35 ers, means whereby the carriage withdraws said latch to release said state-determining member for immediately consequent movement while the carriage is in a computing zone, and stop-means manually settable to different positions to prevent or control said movement of said member 40 when the latch is withdrawn by said carriage, said positions being determinative, in conjunction with the corresponding positions of said state-determining member, of non-operation, 45 additive operation, and subtractive operation of said pinions.

22. In a multiple-register computing machine, the combination with a plurality of sets of computing pinions, indexable drivers therefor, and a general operator for the drivers, of a plurality of 50 spring-driven state-selectors, one for each set of pinions and releasable to cause the general operator to connect the pinions and drivers for a certain computative state, a latch for each spring-driven state-selector normally operative for holding 55 the latter in position for suppressing said certain computative state, universal means common to all the latches and operable for simultaneously withdrawing the latter, a detent-device 60 becoming operative, upon actuation of said universal means to withdraw the latches, for maintaining the latches in their withdrawn positions, and means whereby the cycling of the general operator disables said detent-device, to release 65 the latches from their withdrawn positions and thereby enable them to re-engage said state-selectors upon restoration of the latter.

23. Machine constructed according to claim 22, the universal latch-withdrawing means includ-70 ing a rock-shaft having arms to which the latches are articulated and said detent-device operative to hold said rock-shaft when the latter has been rocked to withdraw the latches.

24. Machine constructed according to claim 75 22 and including a supplementary latch for each

state-selector normally effective to prevent the latter from moving to said certain computative state-determining position when all the first-mentioned latches are released, the several supplementary latches being selectively releasable to thereby effect register-selection in conjunction with the release of all said first-mentioned latches by said universal means.

25. In a computing machine, the combination with a general operator, drivers driven by the general operator, and computing pinions rotatable by the drivers, of a state-determining member differentially settable from a normal position before operation of the general operator to cause the pinions to be reversibly connected to the drivers for addition or subtraction, a restorer for said state-determining member, and means for operating said restorer, said means including a full-revolution cam operable jointly with said general operator and a cam-follower connected to said restorer, said cam timed, relatively to a general-operator cycle, to drive said restorer to restore said state-determining member to said normal position and to then cause said restorer to recede from said state-determining member so that the latter may be set again prior to another general-operator cycle.

26. In a computing machine, the combination with a general operator, a plurality of sets of drivers driven by the general operator, and a plurality of sets of computing pinions connectible to the drivers, of a state-determining member for each set of pinions differentially settable before operation of the general operator to cause the pinions to be reversibly connected to the drivers, the several state-determining members being in the form of parallel elements mounted for individual movement, a restorer extending crosswise of said parallel elements and supported for movement effective to restore said elements, and means for operating said restorer including a shaft extending crosswise of said elements and operable jointly with said general operator, a pair of spaced cams on said shaft, and a pair of followers for said cams connected to said restorer at spaced points, the pairing of the cams and their followers serving to move the restorer in parallelism, said cams timed to drive said restorer to restore said state-determining members and to then cause said restorer to recede so that the state-determining members may be set again prior to another general-operator cycle.

27. In a computing mechanism of the character described having a casing and a general operator, the combination with a set of drivers driven by the general operator, and a set of computing pinions, of a spring-driven normally latched state-determining member releasable for immediate movement of different extents from a neutral position, for causing the pinions and drivers to be connected additively or subtractively, a lever pivoted at the front of said casing, one arm of the lever projecting from said casing and forming a key, another arm of said lever forming a stop for said state-determining member, and means for locating and holding said lever at different stations, said lever arranged to swing its stop-arm in the direction in which the state-determining member moves and being thereby effective to restore the latter to the position in which it may be relatched.

28. The combination with a general operator, a set of drive-racks driven thereby, idlers constantly meshing with the racks, and a set of computing pinions shiftable transversely to mesh with

either racks or idlers, of spaced fixtures supporting a shaft on which said idlers are mounted, a computing-pinion frame having at its sides slots paralleling the racks and slidably fitted to the idler-shaft, a rock-shaft operable by the general operator to rock intermittently in opposite directions prior, respectively, to the advance and return of said racks, two pinion-frame shifters individually loose on said shaft, one shifter presenting an arm having a slotted connection to said computing-pinion frame, said connection coacting with the pinion-frame slots and the idler-shaft to guide the pinion-frame for meshing the pinions with the idlers, said arm when rocked being effective to swing said frame about the idler-shaft to mesh the computing pinions with the racks, the other shifter presenting arms spaced lengthwise of said shaft to align with the sides of the pinion-frame, links connecting said latter arms to said frame-sides, said latter arms effective when rocked, to shift the frame to mesh the pinions with the idlers, and a clutch-element splined to said shaft to engage either one of said shifters.

29. The invention set forth in claim 28, the computing-pinion frame being flanked by said idler-shaft fixtures, so that a part of said fixtures may interlock with a part of the pinion-frame when the latter is shifted to mesh the pinions with the racks or idlers, the interlocking means including notches, extending in intersecting directions, on one part, and a corresponding notch-entering element on the other part, said notches being open at their intersecting ends, and the aforesaid slots of the pinion-frame being also open to facilitate detachment of the pinion-frame.

30. In a computing machine having a set of drive-racks, idlers meshing with the racks, and a set of computing pinions, the combination of a frame for said pinions, transversely shiftable for meshing the pinions with either the racks or the idlers, a single rock-shaft, two pinion-frame shifters loose on said shaft and arranged so that when rocked individually with the shaft, they, respectively, shift the frame to mesh the pinions with the racks or idlers, a clutch-element splined to said shaft to rock therewith and settable therewith to separately engage either pinion-frame shifter, and means settable jointly with said clutch-element and arranged to clear a pinion-frame shifter when the latter is coupled to the shaft by said clutch-element, and to oppose and thereby lock said shifter, when the latter is not so coupled, against frame-shifting movement.

31. In a computing machine having a frame arranged to swing and thereby mesh computing pinions with drive-racks and also arranged to shift parallelly to said racks to mesh the pinions with idlers meshing with said racks, means for so shifting said frame including, in combination, a rock-shaft, a pair of spaced arms loose on said shaft and rigidly connected by a yoke, said arms connected for shifting the frame to mesh the pinions with the idlers, a third arm loose on said shaft between said pair of arms, and connected for swinging said frame to mesh the pinions with the racks, a driving piece fastened to said shaft, and formed to abut, in one-way driving relation, said third arm and also said yoke, and a clutch-element including a pair of spaced ears slidably fitting said shaft, and rigidly connected by a bar splined to said driving piece, said ears being within said spaced arms and flanking said third arm and driving piece, said clutch-element being arranged so that, depending on its position, it may

drive either said pair of arms or said third arm upon the rocking of said shaft in one direction to mesh the pinions either with the racks or idlers, the driving piece, by means of its said one-way driving relation, being effective to return the operated arms upon reverse rocking of said shaft, for unmeshing said pinions. 5

32. In a computing machine having a carriage and a general operator, the combination with a register selectively operable for a certain computing state, of a releasable spring-driven state-determining member, a latch normally positioned for restraining said member, a latch-retractor having a positive one-way driving connection to said latch for retracting the latter, a spring tending to drive said retractor for retracting said latch, a bolt restraining said retractor, means whereby the carriage withdraws said bolt, said retractor being restorable by said general operator, and a resiliently yieldable connection between the state-determining-member latch and the retractor whereby restoration of the latter also effects restoration of the spring-determining-member latch, said resilient connection serving to snap and hold the state-determining-member latch in effective position and being unopposed to the latch-retractor-driving spring. 20 25

33. Machine constructed according to claim 32 and including a manually-operable key effective to withdraw said state-determining-member latch, said resilient connection yielding when said latch is withdrawn by means of said key, and thereby subjecting the latch to spring tension effective to snap the latch to restored position when said state-determining member is restored. 30 35

34. In a computing machine, the combination with a plurality of registers and a general operator therefor, of a plurality of parallel state-determining bars, one for each register, differentially settable before operation of the general operator, to cause the registers to be reversibly operated, a restoring rod extending crosswise of said parallel bars and slidably supported thereon, means for operating said restoring rod including a shaft extending crosswise of said state-determining bars, and operable jointly with said general operator, a pair of spaced cams on said shaft, a pair of followers for said cams, and a pair of links connecting the followers to said restoring rod, the pairing of the cams, followers and links serving to move the restoring rod, slidably supported on said bars, in parallelism, said cams timed to drive said restoring rod to restore said state-determining bars and to then cause said restoring rod to recede so that the state-determining bars may be set again prior to another general-operator cycling. 40 45 50 55

35. In a multiple-register computing machine having a carriage, the combination of a plurality of sets of computing pinions, a plurality of sets of indexable drivers therefor, each driver individually shiftable to indexing position, a single set of carriage-operated driver-shifting denominational trains having branches ramifying to said sets of drivers which are normally disconnected from said branches, carriage-controlled sets of couplers for selectively connecting the sets of branches to the drivers to effect register-selection, each set of pinions being reversibly connectible to its drivers, an individual state-determining member for each set of pinions, means dependent on said sets of couplers whereby, responsive to the carriage-controlled coupling operation on a selected set of drivers, the carriage also causes setting of a corresponding state- 60 65 70 75

determining member, a general operator for said drivers, and means co-operative with the general operator to connect the associated pinions and drivers for the operation determined by the set 5 state-determining member.

36. In a computing machine having a carriage, the combination with a plurality of sets of computing pinions and drivers therefor, and a general operator for the drivers, of selectively 10 conditionable means for each set of pinions and co-operative with the general operator for connecting said pinions and their drivers for adding or subtracting, a spring-driven state-determining member for each set of pinions for conditioning 15 said means, a pair of latches for each state-determining member, one of said latches normally holding said member in neutral position, each pair of latches arranged so that release of said one latch permits said state-determining member to 20 assume an adding position against the other latch and so that the release of both latches permits said state-determining member to assume a subtracting position, means whereby the carriage as it enters a computing zone releases the adding 25 latches selectively, subtraction-setting means operable to release all the subtraction-latches, thereby to cause all the state-determining members, whose adding latches have been released by the carriage, to assume subtracting positions, 30 and manually-settable means for each state-determining member for limiting the movement of the latter to adding position when its adding latch and all the subtraction-latches are released.

35 37. The combination of a general operator, a plurality of sets of drive-racks operable thereby, each set having indexing mechanism, a set of idlers connected to each set of drive-racks, a plurality of sets of computing pinions normally 40 out of mesh with racks and idlers, means primarily adjustable preparatory to a general operator cycle and controllable by said general operator for shifting each set of said pinions into mesh with said drive-racks, and manually-45 settable means supplementing said adjustable means for causing said general operator to shift either set or both sets of pinions into mesh with said idlers.

38. The combination of a general operator, a 50 plurality of sets of drive-racks operable thereby, each set having indexing mechanism, a set of idlers meshing with each set of drive-racks, a plurality of sets of computing pinions normally 55 out of mesh with racks and idlers, and means 55 for transversely and concomitantly shifting either set of pinions to mesh with its associated racks and the other set to mesh with its associated idlers, to cause the general advance of said racks by said general operator to effect addition in one 60 set of pinions and simultaneously subtraction in another set of pinions.

39. The combination of a general operator, a 65 plurality of sets of indexable drive-racks operable simultaneously by said general operator, adjustable means to enable either set of racks to effect addition and the other set effect direct subtraction at the simultaneous advance of said sets, 70 including a set of idlers meshing with the first set of said racks, a second set of idlers meshing 75 with the second set of said racks, and a plurality of sets of computing pinions all normally out of mesh with both the racks and the idlers, and therefore normally incapable of being driven at the advance of the racks; said adjustable means also including a differentially shiftable

state-controlling mechanism to which said sets of pinions are each responsive as a unit; said state-controlling mechanism including (1) means connected to the first set of computing pinions, for shifting them as a unit in either one of two directions which are transverse to each other and also transverse to the common pinion-axis, for meshing said first set of computing pinions with either their racks or their idlers, and (2) means for shifting the second set of computing pinions as a unit either similarly or alternately to the first set of pinions, for meshing said second set of computing pinions with either their racks or their idlers; each of said pinion-shifting means being operable by the 1 general operator concomitantly with the other pinion-shifting means, so that the advance of said racks by said general operator may effect addition in either set of pinions simultaneously with direct subtraction in the other set of pinions, or may effect addition in both sets of pinions, or may effect direct subtraction in both sets of pinions, each set of pinions moreover being operable for either addition or subtraction while the other set remains idle.

40. The combination with a typewriting mechanism including numeral-typing keys and a carriage controlled thereby, of a computing mechanism including a series of registers and indexing devices therefor, each of said registers being operable for either addition or direct subtraction while another register or registers are either adding or subtracting, each register having an individual shiftable state-controller, and a settable carriage-operated multiple master-controlling mechanism to which said state-controllers are responsive either singly or in groups, at such point or points in the travel of the carriage determined by the setting of said multiple master-controlling mechanism, the latter being brought into use automatically, at any selected zone or zones, and determining for every register the state to which that register shall be set by its individual controller.

41. The combination of a general operator, a 45 plurality of computing units operable thereby, each unit including a set of drive-racks having indexing mechanism and including a set of idlers and a set of computing pinions, the idlers and said pinions operable by the racks, and shiftable 50 means for effecting such individual combinations of racks, pinions and idlers, as to enable the racks in each unit to drive the pinions (1) directly or (2) reversely through said idlers, whereby either set of pinions may be driven either forwardly or 55 backwardly independently of the other set of pinions, to cause the advance of said racks by said general operator to effect addition in one unit and concomitantly effect subtraction in another unit, or to add in both units, or to subtract 60 in both units, or to either add or subtract in one unit, while the other unit remains silent at the advance of the general operator.

42. In a combined typewriting and computing machine having a carriage and a general operator, the combination of a plurality of sets of computing pinions, sets of idlers, one set of idlers for each set of pinions, a plurality of sets of racks, one set of racks for each set of pinions, the pinions, idlers and racks in each unit working in 65 parallel planes, indexing mechanism for said sets of racks, including means whereby the racks are controlled denominationally by said carriage, and means controlled by said carriage for combining 70 the pinions, racks and idlers variously in each 75

set, for performing concomitantly either addition or direct subtraction.

43. In a combined typewriting and computing machine having a carriage and a general operator, the combination of a plurality of computing units, each unit including a set of computing pinions, a set of idlers and a set of racks, indexing mechanism for said sets of racks, including means whereby the racks are controlled denominational by the carriage, and means controlled by said carriage for determining, as to every set of advancing racks, whether they shall operate on said computing pinions and idlers to operate the pinions forwardly or reversely, whereby addition may be performed in one unit, while direct subtraction is being performed in another unit, and whereby either addition or direct subtraction may be concomitantly performed in both units, and whereby at the advance of the racks addition or subtraction may be performed in any unit singly.

44. The combination of a general operator, a succession of sets of drive-racks having indexing mechanism, a set of idlers for each set of drive-racks, a succession of sets of computing pinions, and settable means co-operative with said carriage repeatedly in a single run thereof, for variously controlling the drive-racks in the successive sets and the corresponding sets of pinions and the corresponding sets of idlers, for causing all the computing pinions in the various sets to rotate either forwardly or backwardly at the advance of the racks, or causing either set of computing pinions either to add or perform direct subtraction while another set or sets of computing pinions either add or perform direct subtraction or remain neutral, or causing addition to be performed in one set of pinions simultaneously with either subtraction or silencing in one or more other sets of pinions, or causing either simultaneous addition or simultaneous subtraction in the sets of pinions, or addition or subtraction in any set of pinions while all the other sets are silenced.

45. In a combined typewriting and computing machine having a carriage and a general operator, the combination of a plurality of sets of computing pinions, sets of idlers, one set of idlers for each set of pinions, a plurality of sets of racks, one set of racks for each set of pinions, indexing mechanism for said sets of racks, including means whereby the racks are controlled denominational by said carriage, state-controllers individual to said sets of computing pinions, each state-controller being capable of differently combining its associated pinions, idlers and racks, master controlling trains co-operable selectively with said individual controllers, and means settable upon said carriage for operating said master trains.

46. In a combined typewriting and computing machine having a carriage and a general operator, the combination of a plurality of sets of computing pinions, sets of idlers, one set of idlers for each set of pinions, a plurality of sets of racks, one set of racks for each set of pinions, indexing mechanism for said sets of racks, including means whereby the racks are controlled denominational by said carriage, state-controllers individual to said sets of computing pinions, each state-controller being capable of differently combining its associated pinions, idlers and racks, and master controlling mechanism co-operable selectively with said individual controllers, said carriage having a series of adjust-

able tappet-means for repeatedly operating said master controlling mechanism during a single run of the carriage, said master controlling mechanism being co-operable selectively with any of said state-controllers, for independent setting of any one or more thereof differentially in any computing zone.

47. In a combined typewriting and computing machine having a carriage and a general operator, the combination of a plurality of sets of computing pinions, sets of idlers, one set of idlers for each set of pinions, a plurality of sets of racks, one set of racks for each set of pinions, indexing mechanism for said sets of racks, including means whereby the racks are controlled denominational by said carriage, state-controllers individual to said sets of computing pinions, each state-controller being capable of differently combining its associated pinions, idlers and racks, and master controlling trains co-operable selectively with said individual controllers, said carriage having a series of adjustable tappet-means for successively operating said master trains, during a single run of the carriage, each master train co-operable selectively with any of said state-controllers, for independent setting of each thereof, one of said master trains operable to set any selected individual state controller or controllers to addition, and the other of said master trains having means to set any one or more of the individual state-controllers to subtraction.

48. In a combined typewriting and computing machine having a carriage and a general operator, the combination of a plurality of sets of computing pinions, sets of idlers, one set of idlers for each set of pinions, a plurality of sets of racks, one set of racks for each set of pinions, indexing mechanism for said sets of racks, including means whereby the racks are controlled denominational by said carriage, state-controllers individual to said sets of computing pinions, each state-controller being capable of differently combining its associated pinions, idlers and racks, master controlling trains co-operable selectively with said individual controllers, means settable upon said carriage for operating said master trains, said carriage having an adjustable tappet-means for operating said master trains, each master train co-operable selectively with all of said state-controllers, for independent setting of each thereof, one of said master trains operable to set any selected individual state controller or controllers to addition, and the other of said master trains having means to set any one or more of the individual state-controllers to subtraction, and means for returning all of said state-controllers to normal neutral positions.

49. In a combined typewriting and computing machine having a carriage and a general operator, the combination of a plurality of computing units, each including a set of pinions, a set of idlers, and a set of racks, indexing mechanism for said sets of racks including normally disconnected means whereby the racks may be controlled denominational by said carriage, trains for selectively connecting said sets of racks operatively to said carriage, state-controllers individual to said computing units, said connecting trains being co-operable selectively with the state-controllers associated with the selected units, and means settable upon said carriage for operating said connecting trains.

50. In a combined typewriting and computing machine having a carriage and a general oper-

- ator, the combination of a plurality of computing units, each including a set of pinions, a set of idlers, and a set of racks, indexing mechanism for said sets of racks including normally disconnected means whereby the racks may be controlled denominational by said carriage, trains for selectively connecting said sets of racks operatively to said carriage, state-controllers individual to said computing units, said connecting 5 trains being co-operable selectively with the state-controllers associated with the selected units, and master state-controlling trains operated by said carriage for selectively setting said state-controllers to different positions; one of 10 15 said trains operable to set any one or more of said individual state-controllers to addition, and the other of said trains having means to set any one or more of the individual state-controllers to subtraction.
- 20 51. In a combined typewriting and computing machine having a carriage and a series of reversible registers, the combination of individual state-controllers for said registers, master means controlled by the carriage for co-operation differently with the individual state-controllers selectively in different computation zones, keys for altering the positions of the individual state-controllers, one key for each state-controller, and means for permanently detaining each key in 30 either normal or adjusted position.
52. The combination of a general operator, a carriage-mechanism, a plurality of computing units, each unit having a set of indexable drive-racks operable simultaneously by said general operator, and having a set of idlers, and also having a set of computing pinions, adjustable means to enable either unit to effect addition and another unit to effect direct subtraction at the simultaneous advance of said sets of racks, the 35 40 racks, idlers and pinions in each unit working in parallel planes and being combinative independently of the other units, and differentially shiftable state-controllers to which said combinative units are each individually responsive, 45 each individual controller being shiftable to combine its associated racks, idlers and pinions for different operations independently of the remaining controllers, each of said controllers being operable by the general operator, under the control of said carriage-mechanism, concomitantly with the other controller or controllers, so that the advance of said racks by said general operator may effect either addition in either unit simultaneously with direct subtraction in another 50 55 unit, or may effect addition in both units, or may effect direct subtraction in both units, or may effect either addition or direct subtraction in any unit while the remaining unit or units are silent.
53. In a combined typewriting and computing machine having a carriage and a general operator, the combination of a series of registers, an indexing mechanism therefor including means whereby the registers are controlled denominational by the carriage, state-controllers individual to said registers, and duplex master-controlling trains co-operable selectively with said individual state-controllers, one for addition and the other for subtraction; means being settable upon said carriage for selecting the registers and operating the master trains.
54. In a combined typewriting and computing machine having a carriage and a general operator, the combination of a series of registers, an indexing mechanism therefor including means whereby the registers are controlled denominational by the carriage, state-controllers individual to said registers, said carriage having register-selecting tappets adjustable to various computing zones, and means adjustable with said tappets for setting said state-controllers individually to different controlling positions, whereby the character of computations to be performed in the selected registers is predetermined.
55. In a computing machine having a set of computing wheels and pinions for actuating said wheels, a set of racks, a set of idlers meshing with said racks, a general operator for advancing and returning said racks, said pinions being selectively engageable with said racks or idlers for respectively reversing the direction of rotation of said pinions, a shaft operable by the general operator to rock intermittently in opposite directions prior, respectively, to the advance and return of said racks, and separate means actuated by said shafts and operatively connected to said pinions for shifting the latter in relatively transverse directions for engagement with either the racks or idlers.
56. The combination of a general operator, a plurality of sets of drive racks operable thereby, each set having indexing mechanism, a set of idlers meshing with each set of drive racks, a plurality of sets of computing pinions normally out of mesh with racks and idlers and located in the space bounded by the racks and idlers, and means differentially adjustable, for shifting either set of pinions transversely to mesh with either its associated racks or its associated idlers independently of the other set of pinions, to cause the advance of said racks by said general operator to effect addition in one set of pinions and subtraction in another set of pinions, said last named means including a rotary shaft driven by the general operator, a rock shaft operated by said rotary shaft and operatively connected to each set of pinions, and adapted to effect said shifting movements and also to impart a disengaging movement to said pinions at substantially the end of the advance movement of said racks in addition or subtraction.

HENRY L. PITMAN. 60
